By Clarendon Chamberlain Atty.

UNITED STATES PATENT OFFICE.

EMIL R. DRAVER, OF RICHMOND, INDIANA, ASSIGNOR TO B. F. GUMP CO., OF CHICAGO, ILLINOIS, A CORPORATION OF ILLINOIS.

FEEDING AGITATOR.

Application filed December 16, 1921. Serial No. 522,747.

To all whom it may concern:

Be it known that I, EMIL R. DRAVER, a citizen of the United States, residing at the city of Richmond, in the county of Wayne 5 and State of Indiana, have invented certain new and useful Improvements in Feeding Agitators, of which the following is a specification.

My invention relates to machinery for 10 uniformly feeding material to devices which are used for grinding, mixing or blending diverse materials or qualities thereof, such as grain, food materials such as flour or coffee, and feed stuffs for live stock. The object thereof is to create a uniform and regular 15 flow of material to the feed regulating mechanism and prevent impaction or clogging of the materials in their progress to the feed regulator.

20 The principles of my invention are illustrated in the drawings in which Fig. 1 shows a front view of my device as applied to a plurality of feed regulators. Fig. 2 and Fig. 3 are respectively sectional views on the 25 lines 2—2 and 3—3 of Fig. 1.

Further describing my invention with reference to the drawings in which like characters of reference denote like parts throughout; 1 represents a plurality of feed regulators of the general character illustrated in my Patent No. 1,307,349, having a rotatable drum 2 with pockets by the rotation of which the flow of material is measured. 3 represents a mixing trough adapted to receive the discharges from the different feed regulators and to mix them by means of the interrupted screw conveyor 4. A, B and C are hoppers to which material to be mixed is conducted and held for gradual delivery 40 to the feed regulator. But the bulk and weight of the mass may cause the material to become impacted and thus the free flow thereof to the feeder be interfered with or prevented.

45 To prevent such clogging of material in the hopper I provide a stirring element which, as I prefer to construct it, consists of a vertically reciprocating rod 5 within the hopper having a multiplicity of projections such as the cross-pins 6. The upper end of said rod is swingingly suspended at 7 on the arm 8 which passes through the hopper wall 9 and is pivoted at 10 upon bracket 11. Said arm may also be carried

beyond the pivot to form an integral arm or 55 extension 8'.

I have thus far described my invention with reference to the application thereof to the hopper designated as A in Fig. 1. It is clear that when reciprocating motion is 60 given to the stirrer rod the material in the hopper will be kept in a loosened condition adjacent to the rod, such condition extending outwardly therefrom according to the character and consistency of the material in the 65 hopper. To overcome a possibility of the material in the hopper becoming clogged at points laterally removed from the normal operating zone of the stirrer rod with a result that only the material in the said zone 70 will be fed into the feed regulator 1 and that the stirrer rod will continue to operate in this cleared space, the said stirrer is 75 swingingly connected to the arm 8 in such a manner that it will start to swing laterally in opposite directions when it is reciprocated in a cleared operating zone. This swinging movement of the stirrer will automatically increase the area of its normal 80 operating zone and will thereby increase its 85 efficiency.

In the case of material, the particles of which are more or less adherent, or, in the case of relatively large hoppers or bins, it may be necessary to provide two or more of 85 the stirrer rods. A method of doing this is illustrated in the right hand hopper of Fig. 1 designated as B. A rock-shaft 15 mounted in bearings 16 is provided with a plurality of rocker arms 17 extending through openings 18 in the front wall of the hopper 9 and corresponding in number to the number of stirrer rods which are pivoted to the free 90 end of said arms 17.

As a means of giving reciprocating motion to the arms 8 and 17 and thereby to the stirring rods attached to them I provide a rock shaft 20 journaled at 21 on the hopper wall 9 and having outwardly projecting arms 22, the extremities of which are attached by connecting rods 23 to the corresponding extremities of the arms 8' and 24. The said rock-shaft 20 is actuated by any convenient means, as by an arm 26 to the free end of which is attached a pitman rod 27. The said pitman rod is given reciprocating motion by the crank 28 rotated by shaft 29 and driven by belt 30.

The action of the stirring rods 5 may be modified by providing lower arms 22 with openings 22' by means of which the pivotal relation of the lower ends of the connecting rods 23 thereto may be varied, and similar provision for adjustment may be made by forming similar openings in the upper arms, 8' and 24.

A hood or cover 33 on the inside of the 10 hopper adjacent to and over the inwardly projecting arms 8 and 17 prevents the sifting of material through the openings 18 through which the said arms are passed.

I have represented the stirring device in 15 my invention as a rigid rod with cross-pins. It is clear, however, that many variations of the same may be used both rigid and flexible for attachment to the actuating arm, dependent upon the class and character of 20 the material to be fed and the effect thereon which it is desired to produce.

I claim:

1. In a feeding agitator, the combination with a hopper, of a pair of rock shafts journaled exteriorly of said hopper, mechanical means for operating one of said shafts, an arm rigidly carried by each shaft and projecting laterally of said hopper, a rod connecting said arms for operatively connecting 25 said shafts, said hopper having a slot, an arm rigidly carried by one of said shafts and projecting through said slot into said hopper, and a stirrer pivotally connected to the last mentioned arm and adapted to be 30 swingingly reciprocated by the aforementioned elements.

2. In a feeding agitator, the combination with a hopper, of a pair of rock shafts journaled exteriorly of said hopper, mechanical 40 means for operating one of said shafts, an arm rigidly carried by each shaft and projecting laterally of said hopper, a rod adjustably connecting said arms for opera-

tively connecting said shafts, said hopper having a slot, an arm rigidly carried by one of said shafts and projecting through said slot into said hopper, and a stirrer pivotally connected to the last mentioned arm and adapted to be swingingly reciprocated by the aforementioned elements. 45

3. In a feeding agitator, the combination with a hopper, of a pair of rock shafts journaled exteriorly of said hopper, mechanical means for operating one of said shafts, an arm having a series of openings rigidly carried by each shaft and projecting laterally of said hopper, a rod pivotally connecting said arms and adjustable in respect thereto by means of said openings, said rod operatively connecting said shafts, an arm rigidly carried by one of said shafts and projecting into said hopper, and a stirrer pivotally connected to the free end of the last mentioned arm and adapted to be swingingly reciprocated by the aforementioned element. 50

4. In a feeding agitator, the combination with a vertical hopper having a plurality of slots, of a pair of horizontal rock shafts journaled exteriorly of said hopper, an arm having a series of openings rigidly carried 70 by each shaft and projecting laterally of said hopper, a rod pivotally connecting said arms and adjustable in respect thereto by means of said openings, a plurality of arms rigidly carried by one of said shafts and projecting into said hopper through said slots, a hood carried by said hopper for preventing loss of material through said slots, and a stirrer pivotally connected to the free end of each of the last mentioned arms and 75 adapted to be swingingly reciprocated within said hopper.

In witness whereof I have hereunto set my hand at Chicago, Illinois, this 14th day of December, 1921.

EMIL R. DRAVER.
